DENTAL FLASK

William D. Kirby, Arlington, Kans.

Application August 12, 1937, Serial No. 158,791

2 Claims. (Cl. 18—33)

My invention relates to the manufacture of dentures and includes among its objects and advantages the provision of an improved dental flask particularly adapted for duplication work.

5 In the accompanying drawing:

Fig. 1 is an elevational view of my flask;

Fig. 2 is a view along the line 2—2 of Fig. 1 with a portion broken away for the sake of clearness;

10 Fig. 3 is a fragmentary view taken from the position indicated by line 3—3 of Fig. 2;

Fig. 4 is a sectional view along the line 4—4 of Fig. 1;

15 Fig. 5 is a fragmentary view taken from the position indicated by line 5—5 of Fig. 2; and

Fig. 6 is a fragmentary view taken from the 20 position indicated by line 6—6 of Fig. 5.

In the embodiment selected to illustrate my invention, the flask comprises a bottom section 20 10, a middle section 12, a top section 14, and a cover 15 provided with an opening 17. Middle section 12 is made up of two parts 16 and 18, with the part 18 provided with two spaced flanges 25 20 between which the lug 22 carried by the part 16 is loosely positioned. Parts 20 and 22 are provided with aligned openings for the reception of a pin 24 which hingedly connects the parts 16 and 18. Fig. 2 illustrates the parts 16 and 18 in their latched relation.

30 Part 18 carries a finger 26 which lies between lugs 28 on the part 16 and extends a short distance beyond the lugs, as illustrated in Figs. 2 and 3. Finger 26 includes an inwardly extending lug 30 spaced a short distance from the lugs 28. 35 Parts 16 and 18 may be firmly latched in the position of Fig. 2 by driving a tapered pin 32 between the lugs 28 on the part 16 and the lug 30 carried by the finger 26.

Section 10 carries two spaced lugs 34 on opposite sides to have guiding relation with pins 36 formed integrally with the section 12. These pins extend above and below the top and bottom edges, respectively, of the section 12, and the upper ends of the pins have guiding relation with 45 lugs 38 carried by the section 12 on opposite sides in alignment with the lugs 34. The upper ends of the pins 36 include inwardly projecting lugs 40, which lugs are spaced short distances from the lugs 38. Top section 14 may be clamped 50 firmly to the middle section 12 by driving tapered pins 42 between the lugs 40 on the pins 36 and the lugs 38 on the top section 14. Pins 32 and 42 may be serrated along one edge, as at 44, for holding purposes, but good results have been secured with smooth pins.

In Fig. 4, I illustrate the denture generally at 46 while lines 48 and 50 indicate generally lines of separation of the plaster encasing the denture. Means are provided for fracturing the plaster in the middle section 12 on the median line of the 5 denture 46, as indicated by dotted lines 52 in Fig. 2. To this end the parts 16 and 18 are provided with inwardly extending ribs or wings 54 and 56, respectively. In operation, sections 10, 12 and 14 are easily separated while the parts 16 and 18 of section 12 may be separated about the axis of the pin 24. The denture is located in the middle section and is completely surrounded by plaster when the three sections of the flask are assembled. However, when the upper and 15 lower sections of the flask are removed, both faces of the denture are laid bare. Thus the denture will be surrounded by a band only of plaster, which band lies between the denture and the wall of the middle section. The separation 20 of the plaster in the upper and lower sections from the band remaining in the middle section is predetermined in the usual manner.

Because of the wings 54 and 56, the plaster in 25 section 12 will be divided on a median line with respect to the denture 46 while the wings are of such construction as to effectively hold the plaster within the two parts. With the parts 16 and 18 separated, the denture 46 is easily removed from the investment. In separating the 30 parts 16 and 18 with the plaster therein, a pointed tool may be driven between the wings 54 and 56 adjacent the finger 26 for fracturing the plaster. Tapered pins 32 and 42 perform a good 35 clamping function with respect to the middle and top sections 12 and 14, and are easily placed in position and removed.

The keys 32 and 42 draw the contacting edges of the sections 12 and 14 into such pressure relation as to establish a complete seal, thus preventing the escape of excess rubber incident to 40 heating and pressing in the press. In establishing an effective seal about the abutting edges of the sections 12 and 14, I prevent a generally darker base rubber from penetrating natural colored rubber employed on the labial part of the denture.

Without further elaboration, the foregoing will 45 so fully explain my invention that other may, by applying current knowledge, readily adapt the same for use under various conditions of service.

I claim:

1. A dental flask comprising three separable sections, means for holding the sections in assembled relation, one of said sections comprising 55

two parts hingedly connected together, each of said parts having inwardly projecting wings arranged in abutting relation with the wings on the other part in the closed position of the parts, said wings being of such construction and arrangement as to rupture the plaster in the said one section when said parts are pivoted outwardly about their axis.

2. A dental flask comprising a top section, a

bottom section and a middle section between the top and bottom sections, said middle section comprising two parts hingedly connected together, the parts of said middle section being provided with plaster rupturing means for dividing the plaster between a denture located therein and the middle section when said parts are separated about the axis of their pivotal connection.

WILLIAM D. KIRBY.
